INSOLE FOR SHOES AND METHOD OF FORMING SAME

Hiram Gordon, Columbus, Ohio, assignor to The Walker T. Dickerson Company, Columbus, Ohio, a corporation of Ohio

Application November 29, 1932, Serial No. 644,865

6 Claims. (Cl. 36—71)

This invention relates to an improved insole for shoes and the method of forming the same, and the primary object thereof is to form an insole of this character which when built into a shoe will support the foot in the correct manner by effecting the proper retention of the bones comprising the various arches of the foot to thereby prevent pinching of the nerves of the foot muscles and overcome other ailments which would otherwise cause discomfort to the wearer of the shoe.

Another object of the invention lies in the provision of an insole wherein the internal edge portion of the shank thereof is formed with a wing member or extension which, when the sole is incorporated into the shoe will be so positioned or arranged therein as to effect a direct support for the internal part of the longitudinal arch of the foot and at the same time raise and wedge the arch towards the external portion of the foot so that all of the overlying portion thereof may thereby be maintained in its natural normal position.

A further object is to form the wing member or extension flexible or of a hinged nature at the point of connection with the insole proper so that the wing will more readily conform to the shape of the upper and stay in its intended position without special treatment of the leather.

A still further object of the invention is to form the wing extension of the insole from a separate piece of material to thereby eliminate waste in material as it would require a piece of considerable width for forming the wing and sole from one piece.

A still further object of the invention is to provide forward and rearward extensions with the material having the wing thereon which extensions, after being cemented in place on the sole 40 to underlie the inner side of the foot, will serve, together with the wing, to raise the inner side of the foot, focusing the weight of the body at the inner center of the foot and hold the bones forming the various arches wedged and locked in their proper positions.

A still further object of the invention is the provision of an insole which insures the correct weight distribution at the heel of the foot as well as insuring correct tread, thereby relieving the 50 toes of the foot from unnatural strain.

Other objects, advantages and benefits will become readily apparent to persons skilled in the art from a proper consideration of the following description, when taken in conjunction with the 55 accompanying drawings, wherein:

Fig. 1 is a perspective view of an insole blank;

Fig. 2 is a similar view of a separate piece of material adapted to be secured to said blank;

Fig. 3 is also a perspective view of said piece of material slotted longitudinally and edgewise into 60 a pair of layers of which the upper thereof is turned back;

Fig. 4 is a perspective view of a marking template positioned on top of the lower layer of the 65 slotted piece;

Fig. 5 is a view showing a portion of the lower layer removed leaving a wing shaped portion or extension remaining thereon;

Fig. 6 is a detail sectional view taken on the line 6—6 of Fig. 5 to show the beveling of the 70 wing extension;

Fig. 7 is a similar view taken on the line 7—7 of Fig. 5;

Fig. 8 is a view of the piece of material with the wing turned over to show more particularly 75 the beveled edges thereof;

Fig. 9 is a view of the insole and the piece of material with a portion of the wing extension inserted within a side slit formed in the inner edge of the shank portion of the sole;

Fig. 10 is a view with the piece of material cemented in place upon the sole blank;

Fig. 11 is a detail transverse sectional view taken on the line 11—11 of Fig. 10;

Fig. 12 is a view of the under side of the sole 85 showing the same attached to a last;

Fig. 13 is a slightly modified form of invention embodied in a piece of material to be attached to the insole;

Fig. 14 is a transverse sectional view taken on 90 the line 14—14 of Fig. 13;

Fig. 15 is a view of a still further modified form of invention;

Fig. 16 is a transverse sectional view taken on 95 the line 16—16 of Fig. 15;

Fig. 17 is a view showing an insole blank provided with a metatarsal support thereon;

Fig. 18 is a transverse sectional view taken on the line 18—18 of Fig. 17.

Referring more particularly to the drawings 100 which illustrate the various steps in the construction of the improved insole, the numeral 1 designates the completed insole shown in Fig. 10 which sole is formed in two parts designated by the numerals 2 and 3 respectively. The part 3 105 which is cemented in place upon the upper surface of the sole blank or part 2 is formed with a wing extension 4, extending inwardly in an overlying manner from the shank portion of the sole and of a length substantially equal to the length 110

of said shank portion. Also formed with the portion 3 is a rearward extension 5 overlying the inner heel portion of the sole and having its inner edges 6 and 7 skived thin or wedge-like so that when cemented in place, they will lie substantially flush with the upper surface of the sole. The sole provided with the extensions 4 and 5 is placed upon a last 8 as shown in Fig. 12 with the wing extension 4 bent or folded against the side of the last so that when the shoe upper, (not shown) is attached to the sole in the usual manner, the wing extension 4 will be arranged interior of the upper and directed upward against the inner side thereof. By the provision of this wing interior of the shoe and at the inner shank portion thereof, the same will form a rigid support for the arch of the foot and tend to lift or wedge the arch over to its elevated position so as to retain the various bones or joints thereof in their proper natural position. Further, this support together with the extension 5 will raise the inner part of the arch and heel and shift the weight of the body toward the outer portion of the foot and thereby distribute the weight more evenly 25 and correcting the posture of the body of the person wearing the shoe.

Although the wing extension 4 forming the support for the arch of the foot may be formed integral with the sole blank, it has been found desirable to form the same from a separate piece of material in order to provide for certain flexibility at the point of juncture between the wing and sole and to permit the wing to conform more readily to the shape of the last and upper during the manufacture of the shoe. To this end, a method of construction is employed using a number of separate steps which have been shown in Figs. 1 to 9 inclusive in which the sole blank or portion 2 is slit inwardly at the inner edge of the shank portion to provide a longitudinally extending pocket 9 extending substantially the full length of said shank portion. The piece of material designated by the numeral 3 and which may be of any suitable thickness is shaped in outline to conform to the curvature of the outer edge of the sole blank and with the extension 5 matching the inner edge of the heel. Also formed with the piece 3 is an outwardly curved portion which when the piece is attached to the sole 2 provides the wing extension 4. The piece 3 is slotted longitudinally and edgewise from one end thereof to a point even with the extension 5 to provide upper and lower layers 10 and 11 respectively. The layer 10 is then turned back and a marking template 12 is placed upon the layer 11 which template is shaped to conform in outline with that of the wing 4 and is provided with a slotted opening 13 arranged at a point to indicate the normal inner edge portion of the sole blank and the depth of the pocket 9 formed therein. The layer 11 is now marked along the slot and the portion 14 thereof removed as shown in Fig. 5 leaving a portion 15 in place which forms a part of the wing 4. This portion of the material is then beveled at its edges as at 16 and 17 and at its point of connection to the extension 5 is cut transversely, as at 15a, from the edge 16 to the top of the bevel which will leave a slight piece 15b connecting the portion 15 to the rest of the insert. The connecting piece 15b will be outside the normal edge of the insole when the wing extension is secure in place thereon. The wing portion with the edge 16 thereof which is wedge-like in shape is then inserted within the pocket 9 and held in place therein by means of cement

and staples 18 passing through the edge 16 and the sides of the pockets 9. The under surface of the heel extension 5 is also beveled as at 19 after which, the heel extension 5 and the layer 10 is cemented in place upon the upper surface of the sole blank 2 and to the portion 15, thus completing the sole for its positioning upon the last and attachment to the shoe upper as previously mentioned. By this laminated formation of the sole, the latter possesses an unusual rigidity at the shank thereof and yet provides for certain flexibility, particularly of the wing portion 4 and its point of connection to the sole shank. Attaching the wing 4 in the manner described, produces what may be termed a hinge which permits the wing to bend readily adjacent the point of joinder to the blank, conforms to the shape of the last and stay in its intended position within the upper without the tendency of straightening and producing a disfigurement of the upper at this point which would be apt to be the case should the wing be formed integral with the sole blank. The weakening or hinge effect between the wing and the sole blank is therefore an important feature of the invention in that it eliminates special treating of the leather to maintain the wing in its raised or arch supporting position.

In the form of the invention disclosed in Figs. 13 to 17 inclusive, there has been illustrated an additional extension formed with the member 3 of the sole which extension is designated by the numeral 20 and extends forward from the shank portion of the sole to the toe thereof and along the inner portion of the sole thus forming a support for the inner portion of the tarsal arch. The extension 20 has its under surface 21 beveled to a thin edge towards the sole to provide for a smooth gradual slope thereof beginning at the outer edge of the sole. If desired, the rearward extension 22 formed with the material shown in Figs. 15 and 16 may be arranged on the exterior portion of the heel instead of along the inner side thereof as in the preferred form in order to correct certain irregularities or conditions of the foot which may be present.

The improved sole which has primarily been designed for feminine shoes is preferably used in shoe constructions employing a metallic shank stiffener of the type shown in the patent to Anding 1,748,377, issued February 25, 1930, which shank stiffener is positioned substantially centrally and longitudinally of the shoe sole and provides a rigid support for the arch. When a stiffening member of this type is used in connection with my improved insole, not only is the arch of the foot raised to its proper normal position but also, due to the addition of the wing member 4 of the sole, supported and wedged in a position holding the various bones comprising the arch in their proper order, affording relief in cases of the so-called "fallen" arch and provides generally for enhanced foot comfort in shoe construction. In shoes where the shank stiffener is omitted, the insole may be provided with a pad or the like 23 which is positioned on the sole to underlie the joints comprising the metatarsal arch and which pad or support is positioned directly upon the sole portion 2 and covered by the upper layer of the material 3 which also may serve as a sock lining for the shoe.

From the foregoing, it will be seen that there has been provided a novel type of insole and method of forming the same, which sole due to its construction, will effectively support the

arches of the foot as intended by nature and hold the bones thereof in their proper position so as to prevent their spreading or disalignment which would be apt to cause pain and discomfort of the foot. It will also be seen that by forming the various supports integral with the sole, an unusual rigidity thereof is provided and the shape of the sole kept intact under varying conditions of service. Furthermore, by the integral formation of the sole and supports, the latter are held in place upon the sole and prevented from shifting or becoming dislodged.

What is claimed is:

1. The method of forming a shoe insole, which consists in first slitting the sole blank inwardly a predetermined distance from the inner edge of the shank portion of the blank, then shaping a separate piece of material to conform in outline with the outer edge of the shank portion of the blank and having a wing on its opposite edge, then slitting said piece of material edgewise and longitudinally for a distance including said wing to form upper and lower layers, then removing part of the lower layer leaving the wing shaped portion in place, then beveling the inner cut edge of said wing portion and securing the same in place within the slit formed in the shank portion of said blank, and then cementing the upper layer of said material to the lower layer and to the upper surface of said sole blank.

2. The method of forming an insole for shoes which consists in first slitting the sole blank inwardly along the inner edge of the shank portion to form a longitudinally extending pocket, then shaping a separate piece of material to conform in outline with the outer edge of the shank portion of the blank and form the same with a wing extension at its opposite edge, then slitting said piece of material edgewise for a distance including said wing extension to thereby produce upper and lower layers, then marking off the proper width and length of said wing extension upon the lower layer and removing the remaining portion thereof, then beveling the inner marked off edge of said wing extension and positioning said edge within the pocket formed in the shank portion of the blank, and then cementing the upper layer of said material to the upper surface of said blank and wing extension.

3. The method of forming an arch support on an insole for shoes which consists in first slitting the sole blank inwardly a predetermined distance at the inner edge of the shank portion to provide a longitudinal pocket therein, then shaping a separate piece of material to conform substantially with the outline of the outer edge

of the shank portion of the blank and having a wing on the opposite edge thereof, then slitting said piece of material edgewise for a distance including said wing to provide upper and lower layers of said material, then marking off with a templet the inner portion of said wing upon said lower layer and removing the remaining portion of the latter, then beveling the inner edge of said wing portion to the shape of a wedge and positioning said edge within the pocket formed in the shank portion of said blank and securing the same therein, and then cementing the upper layer of the material to the upper surface of said sole blank and to the wing extension attached thereto.

4. The method of forming an insole for shoes which consists in first slitting the sole blank inwardly a predetermined distance from the inner edge of the shank portion of the blank to provide a longitudinal pocket therein, then shaping a separate piece of material having a wing portion and an extension extending over a portion of the heel blank, then slitting said piece of material edgewise from the forward end thereof for a distance including said wing to provide upper and lower layers of said material, then marking off said wing from the lower of said layers and removing the remaining of said material forming said lower layer, then beveling the inner edges of said wing and extension and placing the beveled edge of said wing into the pocket formed in the shank portion of said slitted blank and in then cementing the upper layer of said material to the upper surface of said sole blank and to said wing portion.

5. An insole for shoes comprising a sole blank having a longitudinally extending pocket formed in the inner edge of the shank portion of said blank, a separate piece of material having a portion secured within said pocket forming a laterally extending wing upon said sole, and a portion integral with said material overlying the shank portion of the sole blank and cemented in place thereon.

6. An insole for shoes comprising a sole blank having a longitudinally extending pocket formed in the inner edge of its shank portion, a separate piece of material having a portion secured within said pocket forming a laterally extending wing upon said sole, a portion integral with said material overlying the shank portion of the sole blank and a wedge shaped extension overlying a portion of the heel of the sole blank, said overlying portions being cemented in place upon said sole.

HIRAM GORDON.
